OTHER PUBLICATIONS

Lenovo Yoga Book tablet; published Oct. 17, 2016 [online], [retrieved Sep. 11, 2021]. Available from Internet, URL: <<https://>

FIG. 1 is a front elevation view of a tablet computer showing the new design;

FIG. 2 is a rear elevation view thereof;

FIG. 3 is a left side elevation view thereof;

FIG. 4 is a right side elevation view thereof;

FIG. 5 is a top plan view thereof;

FIG. 6 is a bottom plan view thereof;

FIG. 7 is a rear isometric view thereof;

FIG. 8 is a front elevation view thereof with the stand being in an open position;

FIG. 9 is a rear elevation view thereof;

FIG. 10 is a left side elevation view thereof;

FIG. 11 is a right side elevation view thereof;

FIG. 12 is a top plan view thereof;

FIG. 13 is a bottom plan view thereof;

FIG. 14 is a rear isometric view thereof;

FIG. 15 is an enlarged view of the encircled portion of the tablet computer shown in FIG. 2;

FIG. 16 is an enlarged view of the encircled portion of the tablet computer shown in FIG. 7; and,

FIG. 17 is an enlarged view of the encircled portion of the tablet computer shown in FIG. 14.

The broken lines shown in the drawings illustrate portions of the tablet computer that form no part of the claimed design. In addition, the dot-dash broken lines encircling portions of the tablet computer in FIG. 2, FIG. 7, FIG. 14, and illustrated

(Continued)

in enlarged views FIGS. 15-17 are for the purpose of illustrating enlarged views and form no part of the claimed design.
